WINDOW CLOSURE

Victor I. Zelov, Rosemont, Pa.

Application September 22, 1952, Serial No. 310,760

1 Claim. (Cl. 20—40)

This invention relates to closure members, more particularly to window panes and windows, and has for an object to provide a window pane and windows of novel construction.

Another object of the invention is to provide a plastic window pane so constructed as to expand to more closely grip or engage the window frame upon application of wind or other external pressure thereto.

Yet another object of the invention is to provide a window closure of high structural strength capable of withstanding extremely high wind loads.

The design and construction provides a very high structural strength which permits making larger panes and reducing the cost of the window frames. The design also provides for economical production and the use of plastic materials which will permit of controlled light transmission.

These and other objects are effected by the invention as will be apparent from the following description and claim, taken in accordance with the accompanying drawings, in which:

Fig. 1 is a perspective view of a window pane or closure constructed in accordance with the present invention; and,

Fig. 2 is an enlarged sectional view, taken along the line II—II of Fig. 1, looking in the direction indicated by the arrows.

Referring now to the drawings in greater detail, the reference character 10 indicates a wall having an opening 11 in which is mounted a window frame 12. The top of the wall opening 11 is defined by the lintel 13 and the bottom of the opening by the sill 14.

The present invention is concerned with the window closure or pane, indicated in its entirety by the reference character 15. In the construction illustrated the pane 15 includes a rectangular peripheral portion 16 lying in the plane of the opening 11, and provided with a flange 17 disposed at right angles to the plane of said peripheral portion 16 and serving to strengthen the latter and to provide secure anchorage of the peripheral portion in the mastic or putty 18.

The peripheral portion 16 surrounds a main body portion comprising a central pyramidal portion 20 and

5 an intermediate frusto-pyramidal portion 21, with the base of the central pyramidal portion 20 coinciding with the top of the intermediate frusto-pyramidal portion 21. The tops of the two pyramidal portions 20 and 21 extend in opposite directions, so that the slope of the four flat sections comprising the central portion is the opposite of the slope of the four flat sections comprising the intermediate portion, when considered with respect to the plane of the opening 11.

10 As best shown in Fig. 2, this construction provides a window pane that is "dished" outwardly in overall section, yet has a central portion "dished" inwardly. This not only produces a novel and pleasing appearance, but effects a high degree of resiliency, permitting the pane to 15 "give" when subjected to high wind pressure. The rectangular peripheral portion 16 actually bows outwardly intermediate its corners under application of pressure to the outer surface of the pane.

By having the central portion 20 of the pane disposed reentrantly with respect to the intermediate portion 21, the desired "dished" effect is obtained without having any portion of the pane project outwardly from the plane of the opening 11 a distance sufficient to render the window unsightly.

20 25 In order to obtain a suitable degree of strength it is recommended that a reinforced plastic be utilized, and the desired reinforcing may be obtained by the use of glass fibers, burlap, jute, etc. in a binding medium of any casting type of thermosetting or thermoplastic resin, such as polyester styrene, diallylphtaleate, epoxy resin, etc. By proper selection of reinforcing medium and binding medium, various degrees of light transmission, strength, insulation, resiliency, etc. may be obtained.

While this invention has been illustrated in but one 30 35 form, it will be apparent to those skilled in the art that other shapes and cross sections can be utilized to obtain the desired results without departing from the spirit thereof.

What is claimed is:

40 A window closure consisting of a unitary molded sheet of reinforced plastic comprising a rectangular peripheral portion, a frusto-pyramidal intermediate portion, and a reversed pyramidal central portion whose base coincides with the top of the frusto-pyramidal intermediate portion.
